NOVELTY CONTAINER FOR A BALL-POINT PEN, LIPSTICK, OR THE LIKE

Harry A. Wisotsky, Brooklyn, N. Y., assignor to Hollywood Novelty Company, Inc., New York,
N. Y., a corporation of New York

Application October 9, 1953, Serial No. 27,128

Term of patent 14 years

(Cl. D86—10)

To all whom it may concern:

Be it known that I, Harry A. Wisotsky, a citizen of the United States, and a resident of the Borough of Brooklyn, city of New York, county of Kings, and State of New York, have invented a new, original, and ornamental Design for a Novelty Container for a Ball-Point Pen, Lip Stick, or the like, of which the following is a specification, reference being had to the accompanying drawing forming a part hereof;

Fig. 1 is a front elevation view of the novelty container for a ball-point pen, lip stick, or the like showing my new design.

Fig. 2 is a bottom end view of the design.

Fig. 3 is a top end view of the design.

Fig. 4 is an exploded front elevation view with cap separated from body of the design.

I claim:

The ornamental design for a novelty container for a ball-point pen, lip stick, or the like, substantially as shown.

HARRY A. WISOTSKY.
